UNITED STATES PATENT OFFICE.

HARVEY JOLLY, OF MICHIGAN CITY, INDIANA.

TROLLEY.

1,112,912.

Specification of Letters Patent.

Patented Oct. 6, 1914.

Application filed July 23, 1913. Serial No. 780,619.

To all whom it may concern:

Be it known that I, HARVEY JOLLY, a citizen of the United States and a resident of the city of Michigan City, county of La-
5 porte, and State of Indiana, have invented certain new and useful Improvements in Trolleys, of which the following is a specification.

My invention relates to improvements in 10 trolleys and has for its object the production of a trolley adapted to effectually engage the conductor wire so as to secure an effective electrical connection between the conductor wire and the vehicle and which will engage 15 the conductor wire in such a manner as to minimize the possibility of jumping off the trolley from the wire.

A further object is the production of a 20 trolley which will be of durable and economical construction and efficient in use.

Other objects will appear hereinafter.

The invention consists in the combinations and arrangements of parts hereinafter described and claimed.

25 The invention will be best understood by reference to the accompanying drawing forming a part of this specification, and in which—

Figure 1 is a side elevation of a trolley 30 embodying my invention, the same being shown arranged in contact with a conductor wire, Fig. 2 is a central vertical section of the trolley, Fig. 3 is a top plan view thereof, and Fig. 4 is a vertical transverse section 35 taken on line $\alpha-\alpha$ of Fig. 3.

The preferred form of construction as 40 illustrated in the drawing comprises the conventional trolley pole 1 at the upper end of which is rigidly secured a housing 2, a brace member 3 coöperating with said housing to effect a more rigid connection thereof with the trolley pole. The housing is provided at its upper side with a longitudinally extending channel or recess 4 the bottom of 45 which is of curved formation as clearly shown in Fig. 2. Mounted in the channel 4 is a harp 5 of substantially rectangular form, the under side of said harp being curved to correspond with the curvature of 50 the bottom of said channel so as to permit of rocking movement of said harp relative to said housing in the operation of the trolley. Said harp is secured in position in the channel 4 by means of a transversely extending 55 pin 6 which engages a transversely extend-

ing arcuate slot 7 formed for the reception thereof in the lower portion of harp 5.

The upper side of harp 5 is provided with a longitudinally extending recess 8 for the accommodation or reception of 60 the conductor wire 9. The bottom of the recess 8 is provided with a plurality of transversely extending recesses 10 in which are rotatably mounted contact rollers 11 secured in position by transversely extending pins or bolts 12. The side walls 13 of the harp 5 are provided with transversely extending substantially rectangular slots 14 in which are arranged contact rollers 15 mounted for rotary movement upon vertically extending pins or bolts 16 threaded into the harp 5 as clearly shown in Fig. 4. With this arrangement it will be seen that the bottom and sides of the recess 8 will be lined with contact rollers 70 75 for engagement with the conductor wire 9, the result being alleviation of friction with the advantage of the incidental benefits which arise by reason of such alleviation. The slots 14 for the reception of the contact 80 rollers 15 open laterally in the side walls 13 of the harp which permits of the admission of cool air to said rollers preventing overheating thereof during the use of the trolley. Also by forming said slots directly in the 85 flanges 13 so that the upper sides of said slots are closed by a strap or wall formed integral with said flanges, a strong and durable as well as an economical construction 90 is effected.

Provided at the front and rear ends of harp 5 at the respective extremities of the recess 8 are blades 17 the lower ends of which are rigidly secured to said harp, the upper end portions of said plates being bent 95 outwardly at an angle for projection into close proximity with the under side of the conductor wire when the device is in use. The blades 17 during the use of the device constitute scraping means serving to remove any sleet, ice, or other foreign matter which may gather at the under side of the conductor wire, thereby obviating the difficulties in electrical conduction which otherwise arise by reason of presence of sleet, ice or other foreign matter at the under side of the conductor wire as is generally known. The angular disposition of the upper or ice and sleet contacting edge portions of the 100 blades 17 lends resiliency to said portions of 105 110

said blades which assists in the wire cleaning operation of said blades.

While I have illustrated and described the preferred form of construction for carrying my invention into effect, this is capable of variation and modification without departing from the spirit of the invention. I, therefore, do not wish to be limited to the precise details of construction set forth, but 10 desire to avail myself of such variations and modifications as come within the scope of the appended claim.

Having described my invention what I claim as new and desire to secure by Letters 15 Patent is:

The combination with a trolley pole and a conductor, of a harp adjustably mounted on

the upper end of said pole; contact wheels mounted in said harp, engaging said conductor and maintaining said harp in parallel relation with said conductor; and an ice scraper secured to said harp and inclined upwardly and forwardly from said harp with its upper end spaced slightly from said conductor and adapted to remove ice and sleet from the latter, substantially as described.

In testimony whereof I have signed my name to this specification in the presence of two subscribing witnesses.

HARVEY JOLLY.

Witnesses:

JOSHUA R. H. POTTS,
ARTHUR A. OLSON.
